AUTOMOBILE

Henry J. Keane, Grosse Pointe, Mich., assignor to Chrysler Corporation, Highland Park, Mich., a corporation of Delaware

Application February 19, 1954, Serial No. 29,105

Term of patent 14 years

(Cl. D14—3)

To all whom it may concern:

Be it known that I, Henry J. Keane, a citizen of the United States, residing in the city of Grosse Pointe, county of Wayne, and State of Michigan, have invented a new, original, and ornamental Design for an Automobile, of which the following is a specification, reference being had to the accompanying drawings, forming part thereof, in which:

Fig. 1 is a side elevational view of an automobile showing my new design;

Fig. 2 is a front elevational view thereof;

Fig. 3 is a rear elevational view thereof;

Fig. 4 is a perspective view of the rear of the automobile; and

Fig. 5 is a perspective view of the front of the automobile.

The characteristic features of my design reside in the portions shown by means of full lines in the drawings.

I claim:

The ornamental design for an automobile, substantially as shown and described.
